UNITED STATES PATENT OFFICE.

JAMES McGOVERN, OF TAUNTON, MASSACHUSETTS, ASSIGNOR TO THE WHITE-WARNER COMPANY, OF BOSTON, MASSACHUSETTS, A CORPORATION OF MASSACHUSETTS.

GUARD FOR VALVES OF GAS OVENS.

Application filed November 2, 1923. Serial No. 672,450.

To all whom it may concern:

Be it known that I, JAMES McGOVERN, of Taunton, in the county of Bristol and State of Massachusetts, a citizen of the United States, have invented a new and useful Improvement in Guards for Valves of Gas Ovens, of which the following is a full, clear, and exact description, reference being had to the accompanying drawings, forming a part of this specification, in explaining its nature.

The invention relates to an improvement in guards for gas ovens having a plurality of burners controlled by separate valves and in which it is desirable that gas cannot be turned on to one burner or set of burners while another burner is lighted. Usually the arrangement comprises an oven with gas burners for heating the oven and also a broiler burner with separate valves for controlling the flow of gas to the respective burners. In such case it is desirable that provision be made whereby gas cannot be turned on to the broiler burner while the oven burners are lighted, or vice versa.

The object of the invention is to provide a device or valve control whereby the valve controlling one burner can be opened to permit of the passage of gas to the burner only when the valve controlling the other burner is closed and prevented from being opened. More especially it is the object of the invention to provide a device operating by change in position to control all the valves, and which will have a permitted change of position only when all the valves are closed or in process of being closed; to provide also whereby a closure of certain of the valves may be accomplished automatically by moving said device as well as by independent manual closure, and to provide also whereby movement of said device in some instances can be effected only when certain of said valves have first been manually closed. It is a further object of the invention to provide a device in the nature of an attachment applicable to a certain arrangement of gas manifolds and gas fittings and on which manifolds the device is movable with relation to the valves.

The invention can best be seen and understood by reference to the drawings in which—

Figure 1 is a side elevation of a gas oven

fitted with the improvement constituting the invention.

Fig. 2 is the same as Fig. 1 excepting that the attachment for controlling the valves is shown occupying a changed position from that shown in Fig. 1.

Fig. 3 is a front end elevation of the parts shown in the preceding figures, and

Fig. 4 is a section on the line 4—4 of Fig. 2.

Referring to the drawings:—

1 represents the gas oven. Arranged upon the side 2 of the oven are gas manifolds 3 and 4, respectively, to which gas is fed from a fixture 5. The manifolds are parallelly arranged, spaced some little distance from one another and fixedly secured to act as a mounting for the guard-carrying frame later to be referred to, clips 6 fixed to the side of the oven assisting in the retention of the manifolds. Gas is fed from the manifold 3 to a burner (not shown) arranged within the oven and which, for purposes of illustration, may be considered to be a broiler burner. From the manifold 4 gas is fed to a burner or burners also located within or beneath the oven, which, for purposes of illustration, may be considered to be burners for heating the oven.

Gas is fed from the manifold 3 to the broiler burner through a fixture 7 connecting with the under side of the manifold. Arranged within the fixture for controlling the flow of gas is a valve 8 having a stem 9 turning upon an axis at right angles to the manifold and provided with a handle 10 for turning the stem and thereby opening and closing the valve. The handle 10 turns upon an arc in a plane substantially parallel with the plane of the two manifolds and when the valve is closed the handle will assume a position substantially parallel with the manifold 3 and when the valve is open a position substantially at right angles to the manifold.

Gas is fed from the manifold 4 to the oven burner or burners (two preferably being employed) through fixtures 11 connecting with the under side of the manifold. In each of these fixtures is arranged a valve 12 having a valve stem 13 which turns upon an axis at substantially right angles to the manifold and carries a handle 15 by which the stem is turned. The handle 15 to each

valve turns upon an arc in a plane substantially parallel with the planes of the two manifolds, and when the valve is closed the handle will assume a position substantially 5 in line or parallel with the manifold 4 and when the valve is open the handle will assume a position substantially at right angles to the manifold.

Mounted upon the respective manifolds 10 to slide thereon is a guard-carrying frame 16. The frame is preferably of a generally triangular form and is mounted to slide upon the manifolds through ring-forming connections 17 which embrace the 15 respective manifolds, one ring being provided for the manifold 3 and two rings for the manifold 4. In order that the frame 16 may be conveniently applied to the manifolds the rings 17 are preferably split rings, 20 each ring having an attachable half 17' provided with a flange 18 which is secured to the body of the frame by a screw connection 19. Thus mounted the frame 16 is movable upon the manifolds with a forward and 25 reverse movement and accordingly is movable with relation to the various valves controlling the flow of gas from the respective manifolds.

Carried by the frame 16 are guards 20, 30 21 and 22, respectively. The guard 20 is arranged adjacent the valve 8 of the manifold 3 and the guards 21 and 22 are arranged adjacent the valves 12 of the manifold 4.

35 Each of the guards is made rounding or semi-cup-shaped in form so that as the frame is moved the guard will fit over the handle of the valve to which the guard is adjacent when the handle is occupying a 40 position closing the valve. The guard thus fitting over the handle will then operate to prevent turning of the handle and consequently reopening of the valve until the guard is removed.

45 The guards are so arranged that the guard 20 will fit over the handle 10 to the valve 8 of the manifold 3 by moving the frame in the direction of the valve and the guards 21 and 22 will fit over the handles 15 of the valves 12 to the manifold 4 by moving the frame in a reverse direction. The 50 arrangement of the guards is also such that when the guard 20 is occupying a position fitting over the handle 10 of the valve 8 the guards 21 and 22 will have been moved to a 55 position clear of the handles 15 of the valves 12, thereby enabling the opening of the valves 12. Likewise when the frame has been moved to a position where the 60 guards 22 are occupying positions fitting over the handles 15 of the valves 12 the guard 20 will have been moved to a position clear of the handle 10 of the valve 8, enabling this handle to be turned for opening 65 or closing the valve.

It will accordingly be seen that when gas is flowing out of one manifold to a burner gas cannot be admitted to a burner to which gas is fed from the other manifold and can only be admitted to flow from the other manifold when the flow of gas from the first manifold has been shut off.

In the case of the valve 8 which controls the flow of gas to the broiler burner from the manifold 3, the arrangement is such that 75 the frame cannot be moved to remove the guards from the valves controlling the flow of gas from the manifold 4 until the valve 8 has been manually closed. In other words, the arrangement is such that the valve 8 80 cannot be closed by movement of the frame. To this end the handle 10, which controls the opening and closure of the valve 8, is of a type extending on either side of the axis on which the handle turns and when the valve is open it will lie crosswise the guard in the path thereof and accordingly as the frame is moved the guard will strike the handle which will then prevent further movement of the frame or in any event no such movement as will release the guards from the valves controlling the flow of gas from the manifold 4.

In the case of the valves 12 controlling the flow of gas from the manifolds to the oven burners, it is preferred that these valves may close automatically as the frame is moved for moving the guards over the handles controlling the valves. Inasmuch as more than one oven burner is employed, each controlled by a separate valve, it sometimes happens that one of the valves is closed and the other left open. Accordingly the arrangement is such that as the frame is moved in the direction of the valves 12, 105 the guards 21 and 22 will strike either one or the other or both of the handles 15 to the valves 12 if open and turn these valves into a position closing the valves preliminary to the guards fitting over the handles. If preferred, the valves 12 may be fitted with handles like the valves 8 in which case the frame cannot be moved for moving the guards over these handles until the handles have first both been turned manually to 110 positions closing the valves.

Having thus fully described my invention, I claim and desire to secure by Letters Patent of the United States:—

1. The combination with a gas oven having separate burners, of separate spaced manifolds arranged exterior of the oven and valves controlling the flow of gas from the respective manifolds to the respective burners, a frame mounted to slide upon said manifolds, and guards carried by said frame for preventing opening of the valves when closed, said guards being so arranged that upon moving said frame into a determinate position the valve controlling the flow of gas 120

120

125

130

from one manifold to one of the burners will be left unguarded and the valve controlling the flow of gas from the other manifold to the other burner will be guarded.

5 2. The combination with a gas oven having separate burners, of separate spaced manifolds arranged exterior of the oven and valves controlling the flow of gas from the respective manifolds to the respective burners, a frame mounted to slide upon said manifolds, and guards carried by said frame for preventing opening of the valves when closed, said guards being so arranged that when said frame is moved into a determinate position the valve controlling the flow of gas from one manifold to one of the burners will be open and the valve controlling the flow of gas from the other manifold to the other burner will be closed and prevented

20 from opening.

3. The combination with a gas oven having separate burners, of separate manifolds arranged exterior of the oven and from which gas is supplied to the separate burners, valves controlling the flow of gas from said respective manifolds to the respective burners, a frame mounted to slide with a forward and reverse movement upon said manifolds and to have thereon a limited and defined range of movement, and guards carried by said frame for preventing opening of the valves when closed, said guards being so arranged that when said frame is in one determinate position its guards may leave

35 clear for opening or closure the valve con-

trolling the flow of gas from one manifold and prevent the opening of the valve controlling the gas from the other manifold until said frame has been moved into another determinate position.

40

4. The combination with a gas oven having separate burners, of separate spaced manifolds arranged exterior of the oven one above the other and from which gas is supplied respectively to the separate burners, valves controlling the flow of gas from the respective manifolds to the respective burners, each of said valves being provided with a handle adapted to turn in a plane substantially parallel with the plane of said manifolds for opening and closing the valve, a frame mounted to slide with a forward and reverse movement upon said manifolds and to have thereon a limited and defined range of movement, and guards carried by said frame adapted to fit over the handles of said valves on moving said frame when said handles are in a position closing the valves for preventing turning of the handles and opening of the valves, said guards being so arranged that when said frame is in one determinate position its guards may leave clear for turning the handle of one valve controlling the flow of gas from one manifold and prevent the turning of the handle of the other valve controlling the flow of gas from the other manifold until said frame has been moved into another determinate position.
